VACUUM CLEANER NOZZLE

Adrian E. Ross, Stamford, Conn., assignor to
Electrolux Corporation, Dover, Del., a corpora-
tion of Delaware

Application November 5, 1940, Serial No. 364,396

8 Claims. (Cl. 15—155)

My invention relates to vacuum cleaner nozzles and particularly to nozzles of this type which are connected to a separate motor-fan unit by means of a flexible hose and a rigid hollow member which serves as both a handle for moving the nozzle and as a conduit for conducting air from the nozzle to the hose.

This handle normally extends at an angle from the nozzle and is grasped by the operator near its upper end. In using the device to clean a rug or the like, the nozzle is moved in forward and backward strokes over the rug by means of this handle. During the forward stroke, the force applied by the operator to the handle has a vertically downward component which is added to the weight of the nozzle, thus tending to force the lips of the nozzle more deeply into the pile of the rug. This increases the resistance to movement of the nozzle over the rug. On the other hand, on the backward stroke the force applied to the handle has a vertically upward component which is subtracted from the weight of the nozzle and causes the latter to bear against the rug with less than normal force. This results in reducing the seal between the nozzle lips and the rug, which in turn reduces the amount of air drawn through the rug and consequently adversely affects the cleaning.

One of the objects of my invention is to provide means for compensating for the reversal of the vertical component of the force applied to the handle upon a reversal in direction of movement of the handle and nozzle. In accordance with my invention, means are provided whereby the lips of the nozzle are automatically moved upwardly a slight amount with respect to the lowermost point of the nozzle upon a forward stroke and are moved downwardly slightly upon a reverse stroke.

The preferred structure for carrying out my invention, as well as further objects and advantages, will be apparent from the following description considered in connection with the accompanying drawing which forms a part of the specification, and of which:

Fig. 1 is a rear view, partially in cross section, of a nozzle embodied in my invention;

Fig. 2 is a cross-sectional view, taken on the line 2—2 of Fig. 1;

Fig. 3 is a cross-sectional view on an enlarged scale taken on the line 3—3 of Fig. 1;

Fig. 4 is a cross-sectional view taken on the line 4—4 of Fig. 3; and

Fig. 5 is a cross-sectional view, similar to Fig.

3 but with certain parts in different relative positions.

Referring to the drawing, reference character 10 designates generally a vacuum cleaner nozzle comprising a hollow elongated body member 11. As shown, this body member includes a forward portion 12 and a rear portion 13 which are joined together along the plane of the left-hand portion of Fig. 1 by means of bolts 14. However, this is merely a convenient way of forming the nozzle body, and as far as the present invention is concerned the body could be in one or several pieces.

The nozzle body is formed with a pair of spaced substantially parallel lips 15 and 16 which define between them an elongated suction opening 17. Rotatably mounted in the rear portion 13 of the nozzle body is a handle connection member 18, the outer end 19 of which is adapted to receive and frictionally engage a hollow handle member 19a. The inner end 20 of the connection member 18 is cut away, as indicated at 21, in order to provide for communication with that portion of the hollow body which is between the inlet 17 and a partition wall 22. In the nozzle shown, the body is provided with an additional and smaller suction opening 23, which communicates with a space within the hollow body located between the opening 23 and a partition wall 24. As is clear from Fig. 2, if the nozzle body is rotated about the end 20 of the connection member 18 through 180°, the opening 23 will occupy the position now shown as occupied by the opening 17, and the opening 23 will communicate with the interior of the connection member 18 through the cut-away portion 21. However, the provision of two suction openings forms no part of the present invention.

Each end 25 of the nozzle body is formed with an inclined plane surface 26. A supporting member 27 having an upper inclined surface 28 slidably engages the surface 26. Member 27 has a lower surface 29 which is adapted to slide over a rug or the like undergoing cleaning. As is shown particularly in Fig. 4, member 27 is provided with a projection 30 which extends into a recess 31 formed in the nozzle body. Projection 30 carries a pin 32 on which are mounted rollers 33. The pin may be rotatably mounted in the projection or the rollers may be rotatably mounted on the pin, or all of these parts may be rotatable relative to each other. A pair of retaining plates 34 are secured to the nozzle body by means of screws 35 and serve to retain the member 27 in place. As is apparent from Figs. 3

and 4, the recess 31 has a length several times that of the diameter of the rollers 33, whereby relative limited movement between the members 27 and the nozzle body is permitted.

The lower surface 29 of the member 27 is preferably formed with a groove 36 for the purpose of permitting air to be drawn into the nozzle from those portions of the rug which are underneath the members 27.

In operation, rigid hollow handle 19a is secured to the end 19 of member 18 and extends upwardly at the same angle to the vertical as does the end 19. The upper end of the handle is connected to a cleaning unit by means of a flexible hose. Such cleaning unit is well known and includes a dust-separating member and means, such as a motor-fan unit, to produce flow of air.

In order to clean a rug, the nozzle is moved back and forth over the rug. The suction produced in the hollow member causes air to flow through the material of the rug to the suction opening 17 bounded by the lips 16 and 17. This flow of air removes dirt from the rug as the nozzle is moved thereover. To effect this movement, the operator grasps the upper end of the handle and first pushes forward on the handle and then draws the handle backwardly. On the forward stroke, the force applied to the handle has a vertically downward component which tends to cause the lips 15 and 16 of the nozzle to penetrate more deeply into the pile of the rug. However, on the forward stroke the friction between the rug and the members 27 causes the latter to lag behind the nozzle, thus causing the surfaces 26 of the nozzle body to slide upwardly on the inclined surfaces 28 of the members 27 until the rear ends of the recesses 31 strike the rollers 33. This position of the parts is shown in Fig. 3. On the rearward stroke of the nozzle, the members 27 again tend to lag behind and the parts shift to the position shown in Fig. 5, the relative movement between the nozzle body and the members 27 being limited by the rollers 33 contacting the forward ends of the recess 31. A comparison of Figs. 3 and 5 will clearly show that in the former figure the nozzle lips 15 and 16 are spaced a greater distance from the bottom surfaces 29 of members 27 than they are in the latter figure. As previously explained, this compensates for the variation in vertical force, which tends to push the nozzle into the rug on the forward stroke and tends to lift the nozzle from the rug on the rearward stroke. This not only increases the ease of operation by reducing resistance to movement of the nozzle over the rug on the forward stroke, but also increases the cleaning effect of the nozzle on the rearward stroke by bringing the nozzle lips into better sealing relationship with the rug.

While I have shown and described one more or less specific embodiment of my invention, it is to be understood that this has been done for purposes of illustration only and that the scope of my invention is not to be limited thereby, but is to be defined by the appended claims.

What I claim is:

1. In a vacuum cleaner nozzle, a hollow body member having lips defining a suction opening, structure having substantially flat area slidably engaging a surface to be cleaned for supporting said body member on said surface means for moving said nozzle in forward and backward strokes over said surface, and means operative by virtue of the sliding friction between said structure and said surface for raising said lips relative to said structure upon a forward stroke of the nozzle and

for lowering the lips relative to the structure upon a rearward stroke.

2. In a vacuum cleaner nozzle, a hollow body member having lips defining a suction opening, means for moving said nozzle in forward and backward strokes over a surface to be cleaned, structure slidably engaging said surface for supporting said body member on said surface, and means for movably securing said structure to said body member so that by virtue of the sliding friction between said structure and said surface forward movement of said nozzle over said surface raises said lips relative to said structure and rearward movement of the nozzle over the surface lowers the lips relative to the structure, the last-mentioned means preventing pivoting of said body relative to said structure.

3. In a vacuum cleaner nozzle, a hollow body member having lips defining a suction opening, means for moving said nozzle in forward and backward strokes over a surface to be cleaned, and structure slidably engaging said surface for supporting said body member on said surface, said structure and said body member having co-operating sliding faces, said faces being inclined so that movement of said body member relative to said structure by virtue of the sliding friction between said structure and said surface alters the elevation of said lips relative to said structure while preventing pivoting of said body relative to said structure.

4. In a vacuum cleaner nozzle, a hollow body member having lips defining a suction opening, means for moving said nozzle in forward and backward strokes over a surface to be cleaned, and elements slidably associated with said body member adjacent to either end thereof and slidably engaging said surface for supporting the body member on said surface, said body member and said elements having co-operating sliding faces inclined in such a direction that movement of said body member in a forward direction in relation to said elements by virtue of friction between the surface and said elements raises said lips relative to said elements, said sliding faces preventing pivoting of said body member with respect to said elements.

5. In a vacuum cleaner nozzle, a hollow body member having lips defining an elongated suction opening, a rigid handle connected to said body member and extending upwardly from the rear side thereof for moving said nozzle in forward and backward strokes over a surface to be cleaned, and structure slidably associated with said body member and slidably engaging said surface for supporting the body member on said surface, said structure and said body member having contacting sliding faces inclined upwardly towards the front of the body member whereby movement of said body member forwardly with respect to the structure by virtue of friction between the surface and said structure raises said lips relative to said structure, said faces preventing pivoting of said body member with respect to said structure.

6. In a vacuum cleaner nozzle, a hollow body member having lips defining a suction opening, means for moving said nozzle in forward and backward strokes over a surface to be cleaned, elements slidably associated with said body member and slidably engaging said surface for supporting the latter on said surface, said elements and said body member having contacting sliding faces inclined in such a direction that movement of said body member in a forward direction in

relation to said elements by virtue of friction between the surface and said elements raises said lips relative to said elements, said faces preventing pivoting of said body member with respect to said elements, said body member being formed with recesses elongated in the direction of forward and backward movement, and means carried by said elements and projecting into said recesses for slidably securing said elements to said body member.

7. In a vacuum cleaner nozzle, a hollow body member having lips defining a suction opening, means for moving said nozzle in forward and backward strokes over a surface to be cleaned, elements slidably associated with said body member and slidably engaging said surface for supporting the latter on said surface, said elements and said body member having contacting sliding faces inclined in such a direction that movement of said body member in a forward direction in relation to said elements by virtue of friction between the surface and said elements raises said lips relative to said elements, said sliding faces preventing pivoting of said body member with respect to said elements, said body member being formed with recesses elongated in the direction of forward and backward movement, projections on said elements extending into said recesses, and rollers carried by said projections and engaging

the interior of said recesses for slidably securing said elements to said body member.

8. In a vacuum cleaner nozzle, a hollow body member having lips defining a suction opening, means for moving said nozzle in forward and backward strokes over a surface to be cleaned, elements slidably associated with said body member and slidably engaging said surface for supporting the latter on said surface, said elements and said body member having contacting sliding faces inclined in such a direction that movement of said body member in a forward direction in relation to said elements by virtue of the sliding friction between the surface and said elements raises said lips relative to said elements, said sliding faces preventing pivoting of said body member with respect to said elements, said body member being formed with recesses open at the bottom and elongated in the direction of forward and backward movement, projections on said elements extending through the open bottoms of said recesses, rollers carried by said projections within said recesses, and plate members removably secured to said body members and partially closing said open bottoms for retaining said rollers and slidably securing said elements to said body member.
